UNITED STATES PATENT OFFICE.

ISIDORE SCHWARTZ, OF NEW YORK, N. Y., ASSIGNOR TO ANIMATED PICTURE PRODUCTS CO., A CORPORATION OF DELAWARE.

DISPLAY APPARATUS.

Application filed September 16, 1919, Serial No. 324,138. Renewed May 5, 1925.

My invention relates particularly to an apparatus by means of which pictures or subjects of various kinds may be displayed, but relates especially to such a display apparatus adapted for use in advertising.

The object of my invention is to provide an apparatus by means of which subjects of various kinds may be displayed to great advantage.

Further objects of my invention are to provide an apparatus by means of which a changeable picture may be displayed and in addition thereto a number of other non-changeable pictures may be displayed while utilizing the same source of light as used in connection with the changeable picture.

Still another object of my invention is to provide attractively and uniformly blended lighting effects in connection with the display of pictures above referred to.

Again, another object of my invention is to provide such an apparatus in which the movable picture elements may be readily replaced.

Further objects of my invention will appear from the detailed description thereof contained hereinafter.

While my invention is capable of embodiment in many different forms for the purpose of illustration I have shown only certain forms of my invention in the drawings in which:

Fig. 1 is a front elevation of an apparatus made in accordance with my invention;

Fig. 2 is a plan view of the same;

Fig. 3 is a plan view of a modified form of my invention; and

Fig. 4 is a front elevation of still another modified form of my invention.

Fig. 5 is a vertical section taken on line 5-5 of Fig. 1.

In the drawings, referring to Figs. 1 and 2 I have shown a frame 1 of wood having a recess 2 on its rear face to receive a composite picture 3 which may be enclosed in a permanent metal frame 4 to protect the edges thereof, said slot being also arranged to receive in the rear of the picture 3 a lined screen 5, protected by a metal frame 6 at the edges thereof, and at the rear of the lined screen 5, also, a light-diffusing plate 6^a which may be of glass and which may be enclosed in a metal protecting frame 6^b. The composite picture 3 is comprised of a plate, such for example as glass adapted to trans-

mit light, the same carrying thereon a plurality of pictures each of which is comprised of a plurality of lines so arranged that the lines of one picture fall between the lines of the other picture. The lined screen 5 is comprised of a plate of material adapted to transmit light, such for example as glass carrying a series of parallel lines. The lined screen 5 is spaced a short distance to the rear of the composite picture 3 by reason of the protecting frames 5 and 6. It will be understood that the recess 2 is open at the top but closed at the bottom. At the rear of said recess 2 there are two strips of metal 7 and 8 held in place by screws 8^a which extend over the edge of the recess 2 in order to form a slot with the same for the receipt of the plates 3, 5 and 6^a. Soldered to the strips of metal 7 and 8 there are provided four flanged spacing members 9 said spacing members 9 being soldered at their other ends to a housing 10 having two angular light reflecting surfaces 11 and 12. These surfaces 11 and 12 are turned over at their upper and lower ends so as to secure in place upper and lower closures 13 and 14. Said upper and lower closures support respectively lamp sockets 15 and 16 carrying white or colored lamps 15^a and 16^a to which they are secured by screws 17, while electric connections for the same are made through a socket 18 extending out of the rear of the housing 10. At the forward edge of the upper closure 13 there is a slotted edge 19 formed by bending the edge of the upper closure 13 into the form of an S 20, said slotted edge 19 being provided for supporting in place a picture 21 to be illuminated by reflected light. In order to hold the picture 21 in the most advantageous position, that is to say, so that it will be slightly curved forwardly at the upper edge thereof, a strip 22 is provided which has bent over ends 23 and 24 to receive the edges of the picture 21. At their sides the two reflecting surfaces 11 and 12 also carry slotted edges 25 and 26 made in the same manner as the slotted edge 19 in order to hold in place respectively pictures 27 and 28. These pictures 27 and 28 may be held in a position with the free edges forwardly curved in order to secure the most effective illumination by form strips similar to the strips 22, but preferably instead I use for this purpose wires 29 and 30 having at their outer ends bent over por-

tions 31 and 32 to hold in place the edges of the pictures 27 and 28, said wires being received at their inner ends in recess plates 33 and 34 soldered to the rear of the housing 10.

The modification of my invention shown in Fig. 3 is constructed the same as the form of my invention previously described, except that in this instance the spacing members 9 are omitted, and the sides of a housing 35, made the same as the housing 10 but with the slotted edges 25 and 26 omitted, are secured by screws 37 to the rear of the frame 1 in the place occupied by the strips 7 and 8 in the form of my invention previously described.

In the modification of my invention shown in Fig. 4 I have illustrated a mode of securing variations in blending effects which may be applied to any of the modifications of my invention herein referred to. This is accomplished by providing in the rear of the frame 1 a housing 38 made like the housing 10 or the housing 35 except that in this instance there are provided partitions 39 and 40 which may or may not extend up to the lined screen 5, but which preferably are spaced a distance to the rear thereof dependent upon the degree of blending of the lights desired. In this instance where there are used two partitions 39 and 40 there will be three lamps 41, 42 and 43 used, the lamps 41 and 43 being supported in the same manner as the lamps previously referred to, but the additional lamp 42 being supported upon the partition in a lamp socket 44 provided with current from a socket 45. If the lights 41, 42 and 43 are red, white and blue respectively, the colors which are adjacent to each other will become attractively blended and the blended areas will depend largely upon the particular partition 39 or 40 separating the same. In this way very realistic effects can be obtained approaching the colors of natural objects or scenes, as for example water falls or landscapes, where subjects of this character are displayed by the composite picture 3 carried in the apparatus. However, it will be understood also that without the partitions, blending of colors may also be obtained, but in this instance the individual colors will not be obtainable at the top and bottom of the apparatus in their greatest intensity.

The operation of my invention will be understood from the description of the apparatus given above. From this it will be seen that the electric lamps, whether colored or uncolored, or whether of the same color or different colors, will display the composite picture by transmitting light through the same and when an observer passes in front of the composite picture, first one of the pictures of said composite pictures will be visible and then the other according to which of

the pictures is cut off from view by the interposition of the lined screen between the composite picture and the source of light. The desired lighting effects, whether of the same color or of different colors, and whether widely diffused or diffused to only a small extent can be obtained by utilizing electric bulbs of the desired colors and by making use of the number of partitions, separating the bulbs found most desirable and appropriate for the particular picture being displayed, and by utilizing such partitions of the desired depth. Whenever it is desired to display a different subject this can be readily done by removing the plate 3 from the recess 2 and substituting another composite picture plate for the same. In case the composite picture 3 is the only picture being displayed the form of my invention shown in Fig. 3 will be utilized, but where additional pictures such as the pictures 21, 27 and 28 are to be displayed by utilizing the same sources of light, such pictures are applied to an apparatus such as the apparatus shown in Fig. 1 for displaying the composite picture 3 is utilized to illuminate the pictures 21, 27 and 28 by reflected light. In order to change the pictures 21, 27 and 28, it is merely necessary to remove the strip 22 and wires 29 and 30 and then apply new pictures with said strip 22 and wires 29 and 30 to the apparatus.

While I have described my invention above in detail, I wish it to be understood that many changes may be made therein without departing from the spirit thereof.

I claim:

1. In combination, a frame constructed and arranged to support interchangeable translucent composite pictures and a lamp housing at the rear thereof, provided at the sides thereof with means for supporting interchangeable single pictures, a space being left between the housing and the frame for the passage of light at the sides of the frame whereby the single pictures are illuminated by reflected light.

2. In combination, a frame constructed and arranged to support interchangeable translucent composite pictures and a lamp housing having two reflecting surfaces located at an angle to each other at the rear thereof, provided at the sides thereof with means for supporting interchangeable single pictures, a space being left between the housing and the frame for the passage of light at the sides of the frame whereby the single pictures are illuminated by reflected light.

3. In combination, a frame constructed and arranged to support interchangeable translucent composite pictures, a lamp housing at the rear thereof, provided at the sides thereof with means for supporting interchangeable single pictures in a curved position, a space being left between the hous-

ing and the frame for the passage of light at the sides of the frame whereby the single pictures are illuminated by reflected light, and an upper closure for said housing having a picture receiving slot.

4. In combination, a frame, a translucent composite picture mounted in the frame, a lined screen mounted at the rear of the composite picture and spaced therefrom, a translucent light diffusing member mounted at the rear of the screen and spaced therefrom, and a lamp chamber at the rear of the diffusing member whereby the composite picture may be viewed by transmitted light.

15 5. In combination, a frame, a translucent

composite picture mounted in the frame, a lined screen mounted at the rear of the composite picture and spaced therefrom, a lamp chamber at the rear of the lined screen whereby the composite picture may be viewed by transmitted light, said lamp chamber being provided with a lateral passage for light rays, and a support for display matter mounted in curved position for illumination by light passing through said passage.

In testimony that I claim the foregoing, I have hereunto set my hand this 12th day of June, 1919.

ISIDORE SCHWARTZ.
